UNITED STATES PATENT OFFICE

161,580

GREETING CARD INDEX DISPLAY BOOKLET

Robert M. Garrison, New York, N. Y.

Application November 7, 1947, Serial No. 142,371

Term of patent 14 years

(Cl. D6—2)

To all whom it may concern:

Be it known that I, Robert M. Garrison, a citizen of the United States and residing at 260 West 72nd Street, city, county, and State of New York, have invented a new, original, and ornamental Design for a Greeting Card Index Display Booklet, of which the following is a specification, reference being had to the accompanying drawings, forming part hereof and in which:

Fig. 1 is a front elevational view of the greeting card index display booklet showing my new design; and

Fig. 2 is a top plan view.

I claim:

The ornamental design for a greeting card index display booklet, substantially as shown.

ROBERT. M. GARRISON.
